UNITED STATES PATENT OFFICE.

HARRY TAYLOR MARSDEN, OF HIGHER BROUGHTON, AND FREDERICK JERVIS, OF BURNAGE, ENGLAND.

BEETLING-MACHINE.

1,095,901.

Specification of Letters Patent.

Patented May 5, 1914.

Application filed July 13, 1912. Serial No. 709,274.

To all whom it may concern:

Be it known that we, HARRY TAYLOR MARSDEN and FREDERICK JERVIS, subjects of the King of Great Britain, residing at 5 Higher Broughton, and Burnage, respectively, in the county of Lancaster, England, have invented certain new and useful Improvements in Beetling-Machines; and we do hereby declare the following to be a full, 10 clear, and exact description of the invention, such as will enable others skilled in the art to which it appertains to make and use the same.

Our invention relates to improvements in 15 that type of beetling machines in which the beetling hammers are driven toward the beetling roller and withdrawn from the same by means of a compressed fluid acting upon a piston formed on each hammer or beetling 20 rod, and arranged in a cylinder, the movement of the said piston being controlled by a valve arranged to be operated from a moving part of the machine, or by the piston which it controls, the pressure of the blows 25 given by the said hammer being regulated by altering the pressure of the compressed fluid.

The object of our invention is to provide 30 a construction of beetling machine which is more reliable and efficient than hitherto has been the case. To this end we provide improved means for operating each valve by the movement of the hammer which it controls or by the said compressed fluid; moreover we provide means in the beetle head 35 cushioning the said blow by the aid of the said compressed fluid, and means for rendering any one or more of the hammers inoperative as desired. We attain these objects by the mechanism illustrated in the accompanying three sheets of drawings, in which—

Figure 1 is a detached sectional side view, and Fig. 2 a front view showing one embodiment of our invention. Fig. 3 is a detached sectional side view of a modification. Fig. 45 4 is an enlarged detached front view, and Fig. 5 an enlarged detached sectional side view of a detail of construction. Fig. 6 is an enlarged detached side view and Fig. 7 an enlarged detached front view of another 50 detail of construction.

Similar letters refer to similar parts throughout the several views.

In carrying out our invention the said compressed air or other fluid source may 55 consist of a compressor which may be situated in any desired position, preferably near the

main engine or boilers, to save transmission of power losses. The compressed air, or other fluid under pressure is brought to the machine in pipes, or by any other suitable means. The regulation of the blow may be obtained by means of a variably loaded pressure chamber (like a gasometer) between the machine and the generator of the fluid pressure.

Referring now to Figs. 1 and 2, each hammer *a* is attached by suitable means to a piston *b* working in a cylinder *c*, or other suitable chamber, closed preferably at each end, and each end of the chamber is connected by pipes *d*, *e*, or by any other suitable devices, to one or more valves *f* to an exhaust pipe *g* or receptacle, and also to the supply pipe *h* or receptacle (not shown).

The hammers *a* are connected to the valve 75 or valves *f* by connecting rods *i* which are so made as to be readily detachable, see more particularly Figs. 6 and 7, each moved by a piston *b* and all working on a common crank shaft *k*; the cranks may be formed on the 80 shaft at any desired angle to one another, and the valves *f* accordingly arranged to work in harmony with the said cranks. The crank shaft *k* drives onto an intermediate 85 shaft *l* by means of a chain drive and the intermediate shaft actuates each valve or set of valves *f*, also by means of a chain drive. The chain wheels on the intermediate shaft *l* are mounted on claw couplings which are so arranged that they can only enter into gear 90 in one position so as not to disturb the setting of the valves when thrown in and out of gear, see more particularly Figs. 4 and 5. By this means the valve may be stopped 95 when required while the rest of the machine continues to work. Each valve *f* has two 100 passages which are so arranged as to bring the exhaust and compressed air supply alternately into communication with the opposite ends of the cylinder *c*.

Each hammer *a* is actuated by its valve or valves *f* in the following manner: The valve or valves *f* are in such a position that one end of the cylinder *c* receives fluid pressure, while at the same time the other end of the chamber *c* is open to exhaust *g*. Thus the piston *b* and hammer *a* are propelled, and strike a definite blow. This motion of the piston *b* is transmitted to the valve or valves *f* by the above described device and 105 reverses the position of the said passages thereby opening the first mentioned side of

the cylinder *c* to exhaust and cutting fluid pressure off from the same and closing the second mentioned side of the cylinder to exhaust and opening the same to the fluid pressure, thus bringing the piston *b* and hammer *a* back to the starting position for another blow.

The striking portion of the hammer *a* is provided with a fluid or pneumatic cushion 10 to give a resilient blow, for example of the form shown in Figs. 1 and 2. The hammer *a* comprises a chamber *m* in which a piston *n* works. The piston *n* is provided with a striking piece *o* of any suitable material. 15 The piston *n* receives its fluid pressure on the required side, by for instance, a passage *p* in the piston *b* and hammer rod *r* and non-return valve *g*.

To prevent noise, shocks, or breakages, 20 springs or pads of rubber, or other suitable material may be used where required.

When the main valve or other suitable regulator is opened, the pressure of the compressed fluid accomplishes the work and at 25 the same time controls the machine.

When designing the machine, by setting the cranks at the necessary angle to one another and arranging the setting of the valves accordingly, the hammers *a* may be caused 30 to strike in any order, and at any time which the user of the machine may desire. If any hammer or hammers are not required to work owing to the varying widths of cloth, the supply of air, or other fluid, may 35 be cut off from them by any suitable means, such as for instance valves, or cocks *s*, which may be suitably connected to hand levers *t* arranged to move a supporting piece *u* for holding the respective hammer or hammers 40 out of action and to simultaneously throw out the claw coupling of the chain wheel driving that particular valve and the connecting rod *i* may also be uncoupled, see Figs. 6 and 7.

45 The cloth may be wound upon beams *v*, or may be in flat folds placed under the hammers on a surface plate for flat beetling, as in the old wood faller types.

Any convenient means may be employed 50 to traverse and rotate the beams as required and may be actuated by the power of the fluid, that is a fluid driven engine may be used to do this work.

The speed of the machine, that is the number of blows per minute made by each hammer, is controlled by any suitable, adjustable automatic governor. Any convenient and suitable lifting tackle may be employed if necessary to lift the beetling roller or 55 surface plate according to the type of machine used, that is to say, flat beetling machine or roller beetling machine.

When using compressed air, the same may be cooled before reaching the machine by 60 being passed through any suitable arrange-

ment, such as for example, a coiled pipe immersed in cold water.

To prevent any damage when the machine has to be stopped, both ends of all the cylinders *c* may be arranged with exhaust valves 70 (not shown) which may be opened before the main valve or other suitable regulator is shut.

A suitable guide for example as shown on the drawing is used to prevent the hammers from turning.

According to a modification, and referring to Fig. 3, in lieu of operating the valves *f* by the movement of the piston *b* in the cylinder *c*, we may provide an independent piston *w* and cylinder *x*, which may act by means of the connecting rod *y* on an intermediate shaft *l* or directly on the valves *f*. In this case the piston *w* would be driven by the motive fluid, admitted to the cylinder 80 by a valve actuated from any suitable moving part of the machine and controlled by a governor of the usual type. The hand levers *t* in this instance depend and the slides *z* are situated below the cylinders, as shown 85 in Fig. 3, or in any convenient position. Springs *2* may be provided or a small amount of the motive fluid may be locked at each end of the cylinder by the setting 90 of the valves in order to cushion the pistons and so prevent damage, or both means 95 may be employed.

The hammers are capable of being placed in any desired relative positions to the cloth, that is either above the cloth and striking 100 downward, or below the cloth and striking upward, or at any other angle or position as desired.

The traverse and rotating motions of the beam on which the cloth is being beetled, and the rotating motion of the beam on which the cloth is being placed for beetling when ready, may also be accomplished by utilizing the motive power of the compressed fluid, thus obviating the necessity for any 110 transmission of power by gearing, shafting, pulleys, or other means, from the main engine, other than the fluid pressure in the shape of compressed air, or other fluid or steam.

115 We claim:

1. In a beetling machine of the type hereinbefore referred to, cylinders secured above the beetling roller, to the frame of the beetling machine, ports in each end of each of the 120 said cylinders, a piston in each of the said cylinders, a rod on the said piston, a beetling head connected to the said rod, a driving fluid conduit and an exhaust conduit connected to all the said ports, a valve situated 125 between the ports of each of the said cylinders and the said driving fluid conduit and exhaust conduit for controlling the admission to and exhaust from the said cylinders of the driving fluid, a shaft mounted on the 130

frame of the beetling machine and continuously driven by means of the driving fluid, and gearing between the said valves and the said shaft for the hereinbefore specified purpose.

2. In a beetling machine of the type hereinbefore referred to, cylinders secured above the beetling roller, to the frame of the beetling machine, ports in each end of each of the said cylinders, a piston in each of the said cylinders, a rod on the said piston, a beetling head connected to the said rod, a driving fluid conduit and an exhaust conduit connected to all the said ports, a valve situated between the ports of each of the said cylinders and the said driving fluid conduit and exhaust conduit for controlling the admission to and exhaust from the said cylinders of the driving fluid, a shaft mounted on the frame of the beetling machine and continuously driven by means of the driving fluid, gearing between the said valves and the said shaft, a cut off valve situated between the said driving fluid conduit and each of the said valves, for cutting off the driving fluid from the said valves, slides sliding on the frame of the beetling machine and each operatively connected to one of the said beetling heads, catches mounted on the frame of the beetling machine and each engaging one of the said slides, clutches on the said shaft each engaging and disengaging the gearing between one of the said valves and the said shaft, and hand operated means connected to the said cut-off valves, slides and clutches, for rendering inoperative and holding out of action, any number of the said beetling heads, for the hereinbefore specified purpose.
3. In a beetling machine of the type here-

inbefore referred to, cylinders secured above the beetling roller to the frame of the beetling machine, ports in each end of each of the said cylinders, a piston in each of the said cylinders, a rod on the said piston, a beetling head connected to the said rod, a compressed fluid buffer, situated between the said rod and the said beetling head, and a passage in the said rod and piston, communicating with the cylinder in which the said rod and piston are situated, and with the said compressed fluid buffer, for the hereinbefore specified purpose.

4. In a beetling machine of the type hereinbefore referred to, cylinders secured above the beetling roller, to the frame of the beetling machine, ports in each end of each of the said cylinders, a piston in each of the said cylinders, a rod on the said piston, a beetling head connected to the said rod, a driving fluid conduit and an exhaust conduit connected to all the said ports, a valve situated between the ports of each of the said cylinders and the said driving fluid conduit and exhaust conduit for controlling the admission to an exhaust from the said cylinders of the driving fluid, a shaft mounted on the frame of the beetling machine, gearing between the said valves and the said shaft, and a fluid driven motor operatively connected to the said shaft, for the hereinbefore specified purpose.

In testimony whereof we have affixed our signatures in presence of two witnesses.
